UNITED STATES PATENT OFFICE.

FLOYD S. DONLEY AND JAMES WELSH, OF POTTSTOWN, PENNSYLVANIA.

GAG-OPERATING ATTACHMENT FOR METAL-PUNCHING MACHINES.

1,414,555.

Specification of Letters Patent. Patented May 2, 1922.

Application filed September 19, 1919. Serial No. 324,978.

To all whom it may concern:

Be it known that we, FLOYD S. DONLEY and JAMES WELSH, citizens of the United States, residing at Pottstown, county of 5 Montgomery, and State of Pennsylvania, have invented certain new and useful Improvements in Gag-Operating Attachments for Metal-Punching Machines, of which the following is a specification.

10 This invention relates to metal working machines, and more particularly to a mechanism for automatically operating the gags of a metal punching machine, to regulate the punching operation of the punchers 15 thereof, for permitting the proper spacing of holes punched in metal work.

The gag operating mechanism of approved construction now in use embodies a plurality of levers which are operated to 20 control various combinations of the gags for punching holes in metal, and only a limited number of such combinations, namely from six to eight are permitted with these constructions of gag operated devices, and furthermore the gags are moved into and out 25 of operative relation with respect to the punchers by the levers, one lever being provided for each combination of the gag operation, thereby providing devices which are 30 complex in construction and which require the constant attention of the operator of the punch, to keep the lever and consequently the gags from working out of their proper positions owing to the jar and motion 35 of the machine while working, and this accidental movement of the gags either into and out of operative relation with the punches, often causes extra holes being punched in the metal, consequently spoiling 40 the same, and furthermore the present gag operating devices require an operator who is skilled to a great extent in the metal working art to properly operate them and work out the complicated combinations obtainable to the best advantage of the spacing 45 of the openings on the material to be punched and the marking of the levers accordingly.

It is an object of this invention to provide 50 means for operating the gags of a metal punching machine which will eliminate the inconveniences contingent with the use of the gag operating mechanism now in use, as well as one which may be set by any person of ordinary skill, eliminating the necessity 55 of the employment of highly paid

skilled operators as well as a device which will prevent the accidental operation of the gag and consequently eliminate the chance of error in the punching of the material to 60 a great extent, resulting in a saving of considerable material and time.

A further object of the invention is to provide a device of this nature which is comparatively simple in construction, comprising relatively few parts of different constructions, permitting the maximum production of the parts thereof, in large quantities and consequently reducing the cost of manufacture of the device, as well as to 70 provide one with which corresponding parts are interchangeable so that in case one part becomes broken it may be readily replaced with a new or other part.

More specifically, the invention comprehends the provision of a gag operating mechanism with an automatic release for the gags, which includes a plurality of pivotally mounted levers, which are connected to the gags, and have springs associated therewith for returning them to their normal 75 positions and consequently moving the gags out of operative relation with respect to the punches of the punching machine, and which further comprises a rotary shaft, having a plurality of lever engaging members detachably carried thereby, and also having a hand wheel upon one end which is provided with a plurality of radially extending handles, the said hand wheel being graduated to bear suitable indicia, one corresponding with each of the radial handles carried thereby, which indicia are adapted to indicate various combinations of the lever operating lugs or pins to permit the operation of various of the gags of the punching machine and consequently to regulate the punching action of the punchers thereof. 85 90 95

Other objects of the invention will appear in the following detailed description, taken 100 in connection with the accompanying drawings, forming a part of this specification, and in which drawings:

Figure 1 is a side elevation partly in section of the improved gag operating mechanism. 105

Figure 2 is a vertical cross section through the gag operating mechanism showing it applied to a fragment of an ordinary metal punching machine. 110

Figure 3 is an outer face view of the hand wheel and the radial handles carried there-

by, showing the graduations or indicia carried by the hand wheel.

Figure 4 is a side elevation of a ratchet and its pawl, which are associated with the hand wheel.

Figure 5 is a detail edge elevation of the pawl applied in connection with the ratchet illustrated in Figure 4.

Figure 6 is a detail view of a spring employed in the gag operating structure for automatically returning the levers to the normal positions to release the gags, and

Figure 7 is a plan view of a piece of metal as punched, illustrating the manner of laying out the metal prior to its passage through the punching machine.

Referring more particularly to the drawings, A indicates a fragment of any approved type of metal punching machine, the punches 10 of which are supported by the suitable supporting block 11 and are mounted for reciprocatory movement within the punch carrying block 11, to permit them to be operated idly during the operation of the punch. In punches of this structure gags 12 are employed for preventing the reciprocatory movement of the punches 10 relative to the block 11, when these gags are slidably supported by the block 11, being limited in their sliding movement by bolts 13 which extend through openings 14 formed in the gags. When the gags 12 are forced over the inner ends or heads 15, of the punches 10, the punch is held against reciprocatory movement relative to the block 11, and consequently when it is forced downwardly during the operation of the punching machine A, the punch will punch a hole through the metal being operated upon. However, when the gag 12 is in its outward position as illustrated in Figure 2 of the drawings, the punch 10 will be permitted to reciprocate relative to the block 11 and will not punch openings in the metal being worked upon.

The gags 12, one of which is provided for each punch 10 of the machine A has a hooked link 20 connected thereto in any suitable manner, such as illustrated at 21 in Figure 2 of the drawings, and these hooked links are pivotally connected as shown at 22 to the lower forked end of levers 23. The levers 23 are mounted upon collars 24, which are inturned provided with rectangular axial openings which engage upon the rectangular shaft 25 supported by the end supports 26, of the gag operating mechanism. These supports 26 are attached in any suitable manner, as indicated at 27, to the punching machine A. The levers 23, any desired number of which are provided are mounted for rotary or rocking movement upon the reduced portions of the collars 24, and these collars are held against longitudinal movement upon the shaft by

suitable set screws 28, and spacing collars 29. Coil springs 30 are coiled about the larger or major portions of the collars 24, having one end thereof connected to the collars, while the other end of the spring 70 extends tangentially from the periphery of the respective collar and is connected to its respective lever 23, by angling its terminal and inserting this angled terminal in a suitable recess 31, formed in the lever. These 75 springs 30 automatically release the gags or operate the levers 23 to return them to their normal vertical positions, and move the gags 12 connected with each of the levers, upon operation of the said levers out 80 of movement arresting position with respect to the punches 10.

A second rectangular shaft 32 is carried by the supports 26 and this rectangular shaft has a plurality of discs 33 mounted 85 thereon, one disc for each of the levers 23 as clearly shown in Figure 1 of the drawings. The discs 33 have hubs 34 formed thereon through which set screws 35 extend, for preventing movement of the disc 33 relative to the shaft 32. Each of the discs 33 is provided with a plurality of recesses 36 extending inwardly from the periphery thereof, which recesses extend radially of the axis of the disc and are spaced at predetermined equal distances circumferentially about the disc. These recesses 36 are adapted to receive therein the screw-threaded shank 37 of the lever operating pin 38. These lever operating pins 38 have their outer ends rounded, as shown at 39 for engaging and gradually moving over the rounded ends 40 of the levers 23 to rock them for forcing the gags connected to the respective levers into engagement with the head of the 105 punches 10. It is to be understood that any desired number of the lugs 38 may be attached to each of the discs 33, or any of the discs 33 may be free from carrying these lugs, if desired, depending upon the combination of the punches 10 to be operated for punching the holes in proper spaced relation in the metal being worked upon, a sample of which is illustrated in Figure 7 of the drawings.

A hand wheel 41 is keyed upon the rounded end 42 of the rectangular shaft 32, and this hand wheel 41 has a plurality of handles 43 attached thereto, and extending radially from the periphery of the hand wheel, one handle being provided for each of the recesses 36 formed in the discs 33, it being understood that each of the discs 33 is provided with the same number of recesses, and that all of the corresponding recesses 125 of the disc align longitudinally of the apparatus or parallel with the shaft 32, so that at all times during different positions of the shaft 32 upon rotation thereof, the same corresponding openings in all of the discs 33 130

will be in alignment longitudinally of the mechanism, and also in alignment with their corresponding radial handles 43, carried by the hand wheel 41. This hand wheel 41 has graduations or suitable indicia 45 upon the outer face thereof, in alignment with each of the handles 43, as clearly shown in Figure 3 of the drawings, and while in this figure of the drawings numerals have been illustrated for indicating the various handles, it is to be understood that letters or any other suitable indicia may be employed, without departing from the spirit of this invention.

15 A ratchet wheel 46 is also keyed upon the rounded end 42 of the shaft 32, and it is provided with peripheral recesses 47. The ratchet wheel 46 has exactly twice as many recesses 47 as there are handles 43, the center lines of alternate recesses being parallel to the center lines of their corresponding handle 43, and in alignment therewith longitudinally of the mechanism, while the recesses adjacent the said mentioned alternate recesses are spaced to register between each of the handles and are provided to maintain the punches 10 in neutral, when a pawl 48 is disposed therein. The pawl 48 is pivotally supported as shown at 49, upon one end 20 support 26, and it carries a roller 50 upon one end thereof which is adapted to engage in any one of the peripheral recesses 47 of the ratchet 46. The spring 51 is connected to the end of the pawl 48 opposite that end 25 which carries the roller 50, and tends to urge the roller 50 into any one of the recesses 47, for holding the ratchet 46 and consequently the shaft 32 against accidental rotation.

30 In use, a template is made, in accordance with the openings to be formed in the metal to be worked upon, and after this template has been formed or made, the lever operating pins 38 are arranged on the various discs 33, in accordance with the layout of the 35 openings to be cut, and the operator learns the number of the pin corresponding with each of the handles 43, so that he knows the number and also the location of the pins which are brought into operative relation with the lever 23, when each of the 40 handles 43 are brought into position and when a piece of work, as illustrated in Figure 7 is to be punched it is laid off longitudinally by making relatively short marks at the distance from the forward end of the 45 piece 61 of metal to be worked upon, at which it is desired to punch the various rows of holes or openings, and each mark on the 50 metal the number or indicia corresponding to the handle 43 of the hand wheel 41 which will bring the desired number of the punches 10 into operation upon the operation of the 55 punching machine A, so that when the operator starts the piece of work 61 through 60 the punching machine A, he will move the metal until the punches 10 are over the first line or mark 60 and he will see that the indicia 12 is written thereon to correspond with this mark 60 and he will consequently 65 operate the wheel 41 in a reverse direction until the handle 43 which corresponds to the indicia 12 on the disc 41 is brought into operative position with respect to the levers 23, after which he will move this handle 43 in a 70 reverse direction to drop the levers 23 which are connected to the gags 12, of the puncher 10 corresponding to the number and spacing of openings to be punched in the metal 61 at this first mark 60. The metal 61 is then 75 moved in the punch until the second mark 60 is brought into alignment beneath the punches 10 and the hand wheel 41 is operated, to bring the proper gag in engagement with the proper punches to insure the punching of the desired number of holes through the metal at this point, and in their proper spaced relation. The springs 30 will return the levers 23 to their normal positions immediately after the discs 41 have been moved 80 sufficiently to disengage the pins 38 with the levers 23, consequently preventing the retaining of the gags 12 which are connected thereto in operative engagement with the punches 10 thereby eliminating the liability 85 of punching too many holes in the metal being worked upon.

90 Changes in details may be made without departing from the spirit of this invention, but:

95 We claim:

1. In a gag operating attachment for punching machines, the combination with a plurality of gags, of operating levers therefor, a shaft, selecting means carried by said shaft for manual operation of said levers, means for returning said levers to their normal positions, and means to prevent accidental movement of said selective lever operating means.
2. In a gag operating attachment for punching machines, the combination with a plurality of gags, of operating levers therefor, and selective means for operating said levers comprising a shaft, a plurality of discs mounted upon said shaft, and means carried by said discs for engaging and operating said levers.
3. In a gag operating attachment for punching machines, the combination with a plurality of gags, of levers pivotally mounted and operatively connected to said gags, a shaft, a plurality of discs carried by said shaft, means carried by said discs for engaging said levers to rock the levers for operating said gags, and means carried by said shaft for selecting the disc carried means to be moved into operative engagement with said levers.
4. In a gag operating attachment for

punching machines, the combination with a plurality of gags, of levers pivotally mounted and operatively connected to said gags, a shaft, a plurality of discs carried by said shaft, means carried by said discs for engaging said levers to rock the levers for operating the gags, means carried by said shaft for selecting the disc carried means to be moved into operative engagement with said levers, and means carried by said shaft for preventing accidental movement thereof.

5. In a gag operating attachment for punching machines, the combination with a plurality of gags, of a plurality of pivotally mounted levers, means connecting said levers to said gags for moving the gags upon pivotal movement of the levers, a shaft, a plurality of discs carried by said shaft, radially extending lever operating pins detachably carried by each of said discs and adapted for positioning at various places about the periphery of the discs to be brought into engagement with certain of said levers at predetermined times for rocking the levers to operate said gags.

6. In a gag operating attachment for punching machines, the combination with a plurality of gags, of a plurality of pivotally mounted levers, means connecting said levers to said gags for moving the gags upon pivotal movement of the levers, a shaft, a plurality of discs carried by said shaft, radially extending lever operating pins detachably carried by said discs and adapted for positioning at various places about the periphery of the discs to be brought into engagement with certain of said levers at predetermined times for rocking the levers to operate the gags, a ratchet carried by said shaft, a pawl engaging said ratchet to prevent accidental rotation of the shaft and disc.

7. In a gag operating attachment for punching machines, the combination with a plurality of gags, of operating levers therefor, means connecting said operating levers and gags, a shaft, a plurality of discs carried by said shaft, pins detachably carried by the periphery of said disc, and extending radially therefrom, said pins adapted to engage and rock said levers for operating said gags, a hand wheel mounted upon said shaft, and a plurality of radiating handles carried by said hand wheel and corresponding to the radial pins carried by said disc, for permitting selection of the pin to be moved into operative relation with said levers.

8. In a gag operating attachment for punching machines, the combination with a plurality of gags, of operating levers therefor, means connecting said operating levers and gags, a shaft, a plurality of discs carried by said shaft, pins detachably carried by the periphery of said disc, and extending radially therefrom, said pins adapted to en-

gage and rock said levers for operating said gags, a hand wheel mounted upon said shaft, a plurality of radiating handles carried by said hand wheel and corresponding to the radial pins carried by said disc for permitting selection of the pin to be moved into operative relation with said levers, and springs connected to said levers for returning the levers and bearings to their normal positions after operation thereof by said pins.

9. In a gag operating attachment for punching machines, the combination with a plurality of gags, of operating levers therefor, means connecting said operating levers and gags, a shaft, a plurality of discs carried by said shaft, pins detachably carried by the periphery of said disc, and extending radially therefrom, said pins adapted to engage and rock said levers for operating said gags, a hand wheel mounted upon said shaft, a plurality of radiating handles carried by said hand wheel and corresponding to the radial pins carried by said disc for permitting selection of the pin to be moved into operative relation with said levers, springs connected to said levers for returning the levers and bearings to their normal positions after operation thereof by said pins, a ratchet carried by said shaft, a pivoted pawl, and a spring normally retaining said pawl in engagement with the peripheral recesses in the ratchet.

10. In a gag operating attachment for punching machines, the combination with a metal punching machine, punches and gags therefor, of supports detachably mounted upon said metal punching machine, a shaft mounted within said support, levers pivotally carried by said shaft, a second shaft carried by the supports and disposed above said first mentioned shaft, a plurality of discs carried by said second mentioned shaft, each of said discs having a plurality of recesses therein, lever operating pins detachably carried by said recesses, and means for rotating said second mentioned shaft to operate said levers for reciprocatory movement of said gag to place the punches in operative position.

11. In a gag operating attachment for metal punching machines, the combination with a metal punching machine, punches and reciprocatory gags therefor, of supports detachably mounted upon said metal punching machines, a horizontal shaft rigidly carried by said supports, collars detachably mounted upon said shaft, levers pivotally mounted upon said collars having depending ends, links connecting said reciprocatory gags and the depending ends of said levers, a second shaft rotatably carried by said supports, a plurality of discs detachably carried by said second mentioned shaft, and lever operating pins adjustably carried by said discs for operating said levers at predetermined points,

and manual operating means for rotating said second mentioned shaft to operate the levers of said first mentioned discs for placing the guide pins in operative positions.

- 5 12. In a gag operating attachment for metal punching machines, the combination with a metal punching machine, punches, and reciprocatory gags, of supports detachably mounted upon said metal punching machines, a substantially rectangular shaft rigidly carried by said support, collars detachably mounted upon said shaft, levers pivotally mounted upon said collars, links connecting said levers and said reciprocatory 10 gags, spring means for maintaining said levers in position to move the gags in inoperative position, a second mentioned shaft rotatably carried by said support, a plurality of discs detachably mounted upon 15 said second mentioned shaft, each of said 20

discs having a plurality of recesses therein, lever operating pins adapted to be adjustably positioned within said discs at predetermined points, and a hand wheel for operating said second mentioned shaft, having 25 handles thereon disposed upon said hand wheel and aligning with the recesses in each of said discs for operating the wheel to operate the shaft, and plate selected gags in operative position.

30 13. In a gag operating attachment for punching machines, the combination with a metal punching machine including punches and gags, of rotary means for selective operation of each of said gags, and means for automatically maintaining said rotary means in fixed position for neutral disposal of said 35 gags, when said rotary means is inactive.

FLOYD S. DONLEY.
JAMES WELSH.
